UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

METHOD OF PREPARING PRINTING-PLATES.

1,288,657.

Specification of Letters Patent. Patented Dec. 24, 1918.

Application filed December 13, 1916. Serial No. 136,675.

To all whom it may concern:

Be it known that I, EMIL E. NOVOTNY, a citizen of the United States, residing at Riverside, in the county of Cook and State 5 of Illinois, have invented certain new and useful Improvements in Methods of Preparing Printing-Plates, of which the following is a specification.

This invention relates to an improved 10 method of preparing printing plates having metallic printing surfaces, such as electro-types, stereotypes, and etchings.

As is known to those skilled in the printing art, the usual printing plate, prior to its 15 use on the press, must undergo certain make-ready treatment in order to insure proper results in the printing operation. In preparing the plate, therefore, it is the common practice for the pressman to resort to the 20 use of "underlay" and "overlay", but such make-ready does not of itself form an integral part of the plate, that is to say, is not incorporated in the plate. As contradistinguished from this ordinary practice I 25 propose to prepare the printing plate by such a method, that the necessary or desired make-ready will be incorporated in the plate itself, thereby obviating the use of separate underlay and overlay when the plate is in 30 the press, as my improved plate when completed, will be ready for immediate use, without additional treatment.

Another advantage incident to so incorporating the make-ready in the plate itself, 35 as is done with my invention, is that I am enabled to use, in the preparation of the plate, certain standard make-ready, applicable to the particular press upon which a plate is to be used and this standard make-ready may also be repeatedly employed for 40 the preparation of as many plates as desired. Of course in printing make-ready is required, not only to compensate for errors such as those in the type body but also for 45 errors due to some peculiarity or defect of the particular press. It is therefore the practice for the pressman, on practically every job, to prepare make-ready to compensate for this press defect. The necessity 50 of so preparing the make-ready each time is apparent when it is to be considered that paper or other material of a compressible nature is used for the make-ready and consequently will, during the running of the

press, be more or less affected by the pressure, so that finally it has to be replaced as being no longer accurate. In the practice of my invention I may use make-ready which is standardized or permanently prepared for these press errors, and as such make-ready is 60 only used temporarily in the preparation of the plate and is not used upon the press itself, or during the printing operation, it may be employed in the preparation of other plates.

In the accompanying drawings,

Figure 1 is a cross sectional view taken through a conventional form of casting box and showing a step in the production of the plate.

Fig. 2 is a cross sectional view taken through the plate and its backing after it has been removed from the casting box.

Fig. 3 is a similar view of the plate itself after the phenolic backing has been removed 75 therefrom and after the back of the plate has been shaved to final dimension.

Fig. 4 is a cross sectional view through a curved plate.

In practising the invention the ordinary 80 metallic plate, made in the usual manner from a previously set type body or etching and which plate at this time is of greater thickness than will be finally desired or required, is placed in a rigid proof press which 85 is so constructed as to accuracy, that it will not of itself impart any errors to the proof to be taken. The proof taken on this press will, however, in all probability show certain 90 usual impressional errors due to the irregularities of the plate, and these must be compensated for of course by the usual make-ready, as must also certain errors which will be due to the peculiarities of the particular press upon which the plate is to 95 be finally used. Furthermore, it may be desired to employ make-ready to insure such pressure as may be necessary to obtain a particular kind of printing, such, for instance, as where it is desired to have one part of 100 the printing appear shaded or heavier than another portion.

The proof having thus been taken, the usual corrections thereto are made and the proper amount of make-ready is determined 105 upon, and said make-ready which is in the form of an overlay is placed in its proper position on the proof press, and the plate is

then re-inked and the proof re-taken, and this practice is continued until the print or prints produced from the plate reveal the character of printing desired. The plate 5 and the make-ready are now removed from the proof press and such make-ready which formed overlay on the press is secured to the back of the plate, preferably by pasting its edges thereto and coincident with the type 10 matter to be corrected. The face of such plate is now cleaned, and when dry, is coated with a weak solution of soap and water which acts as a separating medium. The plate which is shown at 1, is now placed 15 with the make-ready so positioned, as illustrated at 2, in a casting box 3. This casting box, as conventionally illustrated in the drawings, includes a bottom or bed 4, upon which are mounted bearers 5, which are arranged to constitute a four sided or rectangular frame, suitable vents 6 being provided for the escape of surplus material, as hereinafter described. The top of the casting box is indicated at 7 and it is to be understood 20 that the casting box may be heated in any manner desired. The plate 1 with the make-ready 2 properly positioned and attached to the bottom thereof, as above mentioned, is placed on the bed of this casting 25 box with the printing or type surface of the plate uppermost, and upon this printing or type surface is placed a layer or sheet 8 of the plastic material, preferably in the nature of a phenolic condensation product of which 30 there are several well known kinds, such as "condensite", or "bakelite". This layer or sheet 8, if desired, is preferably heated prior to placing it upon the plate 2 so that it is in a suitable plastic or soft condition when imposed upon the printing surface of the plate. Pressure is now applied by lowering the top 35 section 7 of the casting box until it rests upon the top faces of the bearers 5. Now it is to be noted that this phenolic product or material shown at 8 even in its plastic condition has but a restricted flow and is confined against undue diffusion or spreading by the frame formed by the bearers 5, and if the top 7 of the casting box be rapidly closed 40 and pressed against the phenolic material 8, the surplus material will escape but slowly through the vents 6. The result will be that the entire cubical area formed by the top and bottom and bearers of the casting box 45 will be completely filled and the plastic or sluggish phenolic material being unable to escape acts as a flexible ram and will push against the metallic printing plate 1 forcing this plate downward so that the make-ready 50 2 will be actually embedded in the bottom of the plate 1 and the entire bottom surface of the plate will be brought to a flat level against the bed of the casting box. Of course this forcing of the make-ready into 55 the body of the plate 1 will result in the

throwing or forcing of a corresponding body of material of the plate at the upper surface or printing face of the plate. In other words, the pressing of the make-ready into the plate will cause a corresponding displacement 70 of the material of the plate, and the phenolic material imposed on the printing surface of the plate being soft, this displacement of the plate material will result in throwing to the printing face of the plate a 75 corresponding or complementary amount of the material so that the make-ready compensation will appear on the printing face of the plate. The casting box may now be permitted to cool and is then opened and the 80 plate with the layer or body of phenolic material thereon is removed from the casting box. The phenolic layer 8 at this time having assumed its set or hardened form may now be placed face downward on a suitable 85 flat, rigid support such as the bed of a shaving machine, and as the bottom of the metallic printing plate 1 is now uppermost the make-ready may be removed or stripped therefrom, leaving irregularities in the back 90 of this plate 1. The bottom or non-printing face of the metallic plate 1 is now shaved to the desired degree or extent so as to present an absolutely flat, smooth surface and when the phenolic layer is stripped from the 95 printing face, the metallic printing plate itself, which is now of the proper thickness and ready for use on the press will appear as shown in Fig. 3. It will be noted in connection with the plate shown in Fig. 3 that 100 material equivalent to the make-ready employed has been caused to appear on the front of the face with the required regularities and irregularities, this taking place as above mentioned during the treatment of the 105 plate in the casting box. I might herein mention that in connection with the making of the plate I may employ what may be termed "standard make-ready"; in other words, a particular press may have certain 110 structural defects therein which may have to be provided for in practically every instance, and in order to embody this in the plate I would previously ascertain what make-ready would be necessary in this connection, and 115 having prepared such make-ready would at the time of treating the plate in the casting box place such standard make-ready on the bed of the casting box or beneath the plate and employ it as a part of the complete 120 make-ready to which the plate was subjected during its preparation. Then when the make-ready is subsequently stripped from the printing plate after the latter has been removed from the casting box this standard 125 make-ready could be laid aside and preserved and then used in the preparation of subsequent plates.

If it is desired to produce a curved printing plate such as is shown at 9 in Fig. 4, this 130

form of plate being adapted for use in connection with the rotary press, I would proceed as above described for the making of the flat plate up to and including the operation 5 of shaving the bottom of the plate. However, instead of then immediately stripping the phenolic layer from the face of the flat plate, I would permit such layer to remain thereon and then subject both the metallic 10 plate and its phenolic layer to the action of sufficient heat to make the phenolic layer flexible and would then subject the metallic plate with such flexible imposed backing layer to the action of a bending machine of 15 any suitable type for the purpose of curving or bending the metallic plate to the desired radius or curvature. Inasmuch as the metallic plate under such circumstances is solidly backed up by the layer of phenolic material I insure that uniformity of curvature 20 throughout the entire area of the plate will be attained with practically no stretching of the printing plate because the bending or curving of the surface of the plate takes 25 place in the neutral arc of the two bodies of material, or the plate and the backing. Consequently, the printing face of the plate will not be distorted. The phenolic backing layer may now be stripped and the curved 30 plate shown in Fig. 4 is the result.

While I have herein shown and described a preferred manner of practising the invention, I wish it to be understood that I do not limit myself to all the details herein set forth 35 by way of illustration, as modification and variation may be made without departing from the spirit of the invention or exceeding the scope of the appended claims.

What I claim is:

40 1. The herein described method of preparing a printing plate which comprises placing a predetermined amount of make-ready material against the back of the plate, imposing upon the face of the plate a body of 45 plastic material and subjecting said plastic material and plate to pressure while in a confined space whereby the make-ready is embedded in the back of the plate, while material of the body of the plate complementary to the make-ready employed is brought 50 to the face of the plate, then removing the embedded make-ready from the back of the plate and then leveling the back of such plate and removing the plastic material from 55 the face thereof.

2. The herein described method of preparing a printing plate which comprises plac-

ing a predetermined amount of make-ready material against the back of the plate, imposing upon the face of the plate a body of 60 sluggish, flowing plastic material and subjecting said plastic material and plate to pressure while in the confined space, whereby said plastic material acts as a ram some of the material of the plate complementary 65 to the make-ready employed is brought to the face of the plate, and then removing the plastic material from such plate.

3. The herein described method of preparing a printing plate which comprises placing a predetermined amount of make-ready material against the back of the plate, imposing upon the face of the plate a body of 70 sluggish, flowing plastic material and subjecting said plastic material and plate to 75 pressure while in a confined space whereby the plastic material acts as a ram the make-ready is embedded in the back of the plate while the material of the body of the plate complementary to the make-ready employed 80 is brought to the face of the plate, permitting said plastic material to set while under pressure, then removing the embedded make-ready from the back of the plate and then removing the plastic material from the face 85 of such plate.

4. The herein described method of preparing a printing plate which comprises placing against the back of the plate a predetermined amount of make-ready material, including make-ready material standardized to the errors of the press upon which the plate is to be used, imposing upon the face of the plate a body of plastic material and subjecting said plastic material and plate to 90 pressure, and then removing the plastic material and the make-ready from the plate.

5. The herein described method of preparing a metallic printing plate which comprises placing a predetermined amount of make-ready material against one face of the plate, imposing upon the opposite face of the plate a body of plastic material, subjecting said plastic material and plate to pressure in a 100 confined space, whereby the plaster acts as a ram certain of the material of the plate is forced by the make-ready to the opposite surface from the make-ready, and then removing the make-ready, then shaving the 105 back of the plate and then removing the 110 plastic material from the plate.

In testimony whereof I affix my signature.

EMIL E. NOVOTNY.
